UNITED STATES PATENT OFFICE.

JOHN H. MORGAN, OF CHICAGO, ILLINOIS, ASSIGNOR TO AMERICAN MORGAN COMPANY,
OF MORGAN PARK, ILLINOIS, A CORPORATION OF SOUTH DAKOTA.

EXCAVATING ATTACHMENT FOR MINING-MACHINES.

1,196,135.

Specification of Letters Patent. Patented Aug. 29, 1916.

Application filed August 6, 1910. Serial No. 575,962.

To all whom it may concern:

Be it known that I, JOHN H. MORGAN, a citizen of the United States, residing at Chicago, in the county of Cook and State of Illinois, have invented certain new and useful Improvements in Excavating Attachments for Mining-Machines, of which the following is a specification.

This invention relates to excavating machines, and more especially contemplates an attachment for any standard type of mining machine.

The primary object is to provide a machine having an improved construction, combination and arrangement of parts adapting it to be used co-operatively with a mining machine, and to perform part of the work heretofore imposed upon the latter machine.

20 One of the main objects of the present invention is to provide improved means for breaking down the material which is being mined.

Another object is to provide improved 25 means for co-operatively mounting and operating a plurality of drills and breaking down wedges.

Another object is to provide improved 30 means for elevating the drilling and wedging devices and for varying the angles at which they operate.

Other and further objects will appear in the specification and be specifically pointed out in the appended claims, reference being 35 had to the accompanying drawings exemplifying the invention and in which—

Figure 1 is a side elevation of an excavating machine constructed in accordance with the principles of the present invention. Fig. 2 is a top plan view of the same, parts being broken away. Fig. 3 is a front elevation of the same. Fig. 4 is a rear elevation of the same. Fig. 5 is a section on the line V—V Fig. 2. Fig. 6 is an enlarged detail elevation of some of the parts shown in Fig. 5. Fig. 6^a is a fragmentary view showing the connections between some of the parts shown in Fig. 6. Fig. 7 is a fragmentary view showing some of the details 45 of Fig. 5 on an enlarged scale. Fig. 8 is a side elevation of a modification, parts being broken away. Fig. 9 is a top plan view of

the embodiment shown in Fig. 8. Fig. 10 is a rear elevation of a portion of the embodiment shown in Figs. 8 and 9. 55

Referring first to the embodiment shown in Figs. 1 to 7 inclusive, a mining machine which may be of any suitable construction or standard type, is represented in dotted lines at 1 (see Figs. 2, 3 and 4), through the 60 side of which project from an endless belt or chain a plurality of horizontal holders 2 for grooving tools 3. Parallelly disposed with reference to the mining machine 1, is an excavating machine, the base member or 65 frame 9 of which is releasably locked to the base frame of the mining machine 1, by means of a pair of lever arms 4, which are pivotally mounted at 5 in a pair of lugs 6 which project from one of the side frames 70 of the base member of said excavating machine. The outer ends of the locking arms 4 are crooked at 7 in the manner shown in Figs. 3 and 4, said arms being thereby adapted to engage the side rail 8 of the 75 adjacent side frame of the base member of the mining machine. As shown best in Fig. 1, the base member 9 of the excavating machine is constructed of small height adapted to be disposed within a horizontal groove 80 10 which is cut into the material to be mined adjacent the floor of the mine by the mining machine 1. Upon the forward end of the base member 9 is mounted a pair of sprockets 11 over which travels an endless belt 85 conveyer 13 of any suitable construction, said conveyer being supported adjacent the rear end of the excavating machine by a pair of sprockets 14 mounted on a shaft 15 journaled in the outer end of an upwardly 90 inclined support or frame 16. As shown in Fig. 2, the shaft 15 has keyed thereon outside of one of the sprockets 14, a sprocket wheel 17 to which power is transmitted by a sprocket chain 18 deriving its power from 95 a lower sprocket 19 on a transverse shaft 20. Said transverse shaft 20 has keyed to its other end a spur gear 21 in mesh with a second spur gear 22, on a drive shaft 23 of a motor 24 rigidly mounted on the rear 100 end of the base member of the excavating machine.

Projecting vertically from the base member 9 of the excavating machine are a pair

of forward guides or ways 25, and a pair of rearward guides or ways 26, said guides being disposed preferably adjacent the longitudinal center of the base frame 9 and spaced apart for a purpose to be hereinafter made clear. In order to provide means adapting said guides to cooperate with other means mounted on a table or support to be presently referred to, said guides are provided along one edge with racks 27, said racks extending throughout the greater portion of the length of said guides. The guides 25 and 26 are rigidly connected above by side rails 28 and cross rails 29, one of said side rails 28 being provided with an overhanging arm or projection 30, within which and a bearing pedestal 31 on the base member 9 is rotatably mounted a vertical shaft 32 provided with a longitudinal slot 33 extending approximately the entire length of said shaft. A suitable support for the breaking down tools is provided preferably in the form of a table or plate 34 which is supported by a plurality of bearing blocks 35 and 36 reciprocably mounted upon the uprights 26 and 25 respectively. A transverse shaft 37 is journaled in the bearing blocks 35, while a transverse shaft 38 is journaled in the bearing blocks 36. On each end of the shaft 37 is a pinion 39 which meshes with one of the racks 27 on the upright 26, while on each end of the shaft 38 is a pinion 40 meshing with the rack 27 on the guide 25, said pinion being adapted to impart a vertical movement either upwardly or downwardly to said table 34. For this purpose a worm gear 41 is keyed to the end of the shaft 37, and meshes with a worm 42 on the short shaft 43, which may be rotated by a crank 44 to raise and lower the rear portion of the table 34. The worm gear 45 carried by the shaft 38 is in a similar manner driven by a worm 46 on the shaft 47 provided with a crank 48 whereby the forward end of the table 34 may be raised and lowered, these devices being operable independently of each other to provide means whereby the table 34 may be tilted into different angular positions for facilitating the work at certain stages of the operation. As will be seen from reference to Figs. 1, 5 and 7 of the drawings, the rear end of the table or support 34 is provided with a vertical projection or rail 49 provided with a plurality of threaded perforations. A pair of bearing brackets 50, 51 rigidly mounted upon the table or plate 34 in coaxial alignment with each threaded perforation in the projection 49, serves to mount or carry an axially movable tool 52, which, in the present embodiment is in the form of a drill. The drill rod 52 is provided with a screw-thread running from its rear end forwardly for a considerable portion of its length, and is pro-

vided with a feather or spline way 53 for the reception of a key or spline 54, which is carried by a sprocket 55 carried by said rod 52 between the threaded projection 49 and bracket 50. It will be evident from the construction described that as the drill rod 52 is rotated in the manner to be hereinafter described, the drill point 56 of the rod 52 is forced forwardly into the wall of the material. On the forward end of the drill rod 52 is provided a rigid collar or flange 57 against which abuts a wedge-shaped block 58 which is perforated in the manner indicated to adapt it to be reciprocably mounted on the forward end of the rod 52. Said block 58 is adapted to effect a wedging action upon that portion of the material below the drill 56 after said drill has been forced into the material, by being provided below with an inclined face 59. As shown in Figs. 2 and 5, the wedge block 58 is made of such a size at its forward end as will adapt it to fit within the hole made by the drill 56. Within the table or plate 34 is provided a groove or guide-way 60 (see dotted lines in Figs. 5 and 6) within which the lower face of the wedge block 58 slides, and held with its side faces vertical. As the drill 56 is fed into the material to be mined, the threaded rear end thereof is fed through the threaded perforation in the projection 49 and fed forwardly, the collar or shoulder 57 finally coming into engagement with the wedge block 58 and forcing it forward in turn to effect a wedging action upon the material, as indicated in Figs. 1 and 5.

In order to provide additional means for driving the wedge block to its work, a reciprocating block or hammer 61 is slidably mounted upon the rod 52 and interposed between said hammer 61 and the lateral face of a bearing block 62 is interposed a resilient member in the form of a spring 63, which tends to drive the hammer 61 against the collar 57. The hammer 61 is provided with a forwardly projecting portion 64 which overreaches the shoulder 57 and is adapted to impinge directly upon the wedge block 58 to drive it forward. The lower end of the hammer 61 is reciprocably mounted in the slot 60. A connecting rod 65 pivoted at 66 on the hammer 61 is provided at its other end with a slot 67, within which the crank pin 68 of the short crank shaft 69 oscillates during the operation of the hammer. The crank shaft 69 is journaled at one end in a bracket 70 mounted on the table plate 34, and at its other end within the bearing block 62. The bevel gear 71, which is freely rotatable on the crank shaft 69, is provided on its rear face with a driving pin 72 which is adapted to impinge against the crank arm of the crank shaft 69, and force the same around into

the position shown in Figs. 5 and 6. When the parts are in this position, a very little movement of the crank pin 72 forces the crank pin 68 into a position in which the spring 63 is free to drive the hammer 61 forwardly to strike a blow on the wedge block 58. The bevel gear 71 is driven by a second bevel gear 73, which is splined to the drill rod 52 and receives its power therefrom. As shown in Fig. 2, a plurality of drill rods 52 of exactly similar construction are mounted upon the table plate 34, said drill rods being connected up to rotate in unison by means of an endless sprocket chain 74, which travels about the sprockets 55. One of the drill rods 52, preferably the one farthest from the mining machine 1, has a second bevel gear 75 splined thereto, which meshes with another bevel gear 76 which is keyed to a short shaft 77 journaled in a box or bearing 78. Upon the outer end of the shaft 77 is keyed a bevel gear 79 which meshes with a bevel gear 80 splined to the vertical shaft 32. A pair of bevel gears 81 are free to rotate upon the vertical shaft 32, but are held against axial movement thereon in the positions shown in Fig. 1, in which they are spaced apart and oppositely disposed with reference to each other. Splined to the shaft 32 and interposed between the gears 81 is a clutch 82 which is movable along the shaft 32 into and out of clutch engagement with either of the gears 81. A bevel gear 83 keyed to the end of a drive shaft 84 meshes with both of said gears 81, rotating one of them in one direction and the other in the opposite direction. It will thus be seen that the rotation of the shaft 32 depends upon which of the gears 81 is connected by the clutch 82 to drive said shaft 32. Upon the outer end of the motor shaft 23 is keyed a bevel gear 85 in mesh with the bevel gear 86 on the rear end of the drive shaft 84 by means of which connection power is transmitted to the gears 81.

At the beginning of the drilling operation, the screw-threaded shafts 53 project rearwardly from the brackets 50 some distance, and the brackets 51 are also initially in positions near the rear end of the guide-ways 60. When the shafts 53 are rotated by means of the sprockets 55, they are screw-threaded through the stationary brackets 49 as shown in Fig. 7, and the drills are thus fed forwardly. At the same time the brackets 51 will be moved forward slowly, thereby slowly moving forward the various hammer devices. These movements may be secured by the construction shown in Fig. 6^a, wherein it will be seen that the screw-threaded shaft 53 passes loosely through the bracket 51, but is threaded through the nuts 73' and 73'' and also through the bevel gear 73. The nuts 73'

and 73'' and the bevel gear 73 are splined to the screw-threaded shaft 53, so that they must rotate therewith. By removing the keys, the nuts and the bevel gear 73 may be rotated to adjusted position so as to vary the position of the bracket 51. In this manner, the time at which the hammer devices go into operation may be varied as desired so as to secure the desired depths of cut before the wedges act on the material to dislodge the same.

When the drill 56 approaches the limit of its forward movement, the collar 57 will engage the wedge 58, as shown in Fig. 5. As soon as this occurs, the wedge is placed in the path of the hammer 64. The drilling operation may still be continued, but mainly for the purpose of enabling the hammer devices to exert repeated hammer blows on the wedges so as to effectually break out the material from the mine walls preferably in large blocks, as shown in Fig. 5.

Referring now to Figs. 8, 9 and 10 of the drawings, which show another embodiment of the invention, a table plate 34' of similar construction to the table plate 34 already described, is provided with slots or guide ways 60', within which reciprocate the wedge blocks 58', said wedge blocks being reciprocably mounted upon the drill rods 52' similarly to the former embodiment. Said drill rods 52' are driven in exactly the same manner which need not be again described, with the exception that the vertical shaft 32' is provided with a flexible universal coupling 87, and a sliding shaft section 88, which is held against rotation relatively to the gear 89. Said gear 89 is driven by the drive shaft 84' through the medium of bevel gear 83'. In this embodiment of the invention, the table plate 34' is pivotally mounted by means of bearing brackets 90 and 91 upon its under face, on a transverse shaft 92 provided on one end with a crank arm 93. A pair of screw standards 94 are rigidly connected above by a cross bar 95 and supported below at 96 on the base member 9'. Threaded to the screw standards 94 are a pair of nuts 97 threaded interiorly and provided on their outer peripheries with worm gears as shown. Meshing with the nuts 97 are a pair of worms 98 which are keyed to the cross shaft 92 so that when the crank arm 93 is revolved, a vertical movement is imparted to the table plate 34'. The cross shaft 92 is journaled in a pair of blocks 99, each of which is bifurcated to permit one of the worm nuts 97 to be interposed between the arms thereof. Upon one of the bifurcated blocks 99 is rigidly secured a toothed sector 100, within the notches of which a bolt 101 is adapted to engage to hold the table 34' in any angular position to which it may be moved. A resilient member or

spring 102, which exerts a tension between the loop end of the bolt 101 and a lug 103, within which said bolt is reciprocably mounted, tends to hold said bolt within a notch in the sector 100. For driving the shaft 84' any suitable means may be interposed between the motor and the shaft whereby the direction of rotation may be reversed, or, if desired, a reversible motor 10 may be employed in order to provide means for retracting the drill rods 52' after they have reached the limit of their forward movement.

What I claim is:

15. 1. In a mining machine, the combination with a mining tool, of means for operating the same, a wedge on said mining tool, and power means for moving said wedge longitudinally of said mining tool to break down material from the mine wall.
20. 2. In a mining machine, the combination with a mining tool, of means for operating the same, a wedge carried by said mining tool, and automatic mechanism for striking said wedge a hammer blow to break down material from a mine wall.
25. 3. In a mining machine, the combination with a frame, of a conveyer capable of having its forward end portion extended into an under-cut in a mine wall, cutting mechanism, a wedge carried by said cutting mechanism, and automatic mechanism for actuating said wedge on said cutting mechanism to break down material onto said conveyer.
30. 35. 4. In a mining machine, the combination with a conveyer adapted to extend into an under-cut in a mine wall, of cutting mechanism above said conveyer, and wedge apparatus slidable on said cutting mechanism for breaking down material from the mine wall onto said conveyer.
40. 45. 5. In a mining machine, the combination with a conveyer, of a mining tool mounted above said conveyer, means for operating said mining tool, a wedge slidably mounted on said mining tool, and power mechanism for operating said wedge to break down material from the mine wall onto said conveyer.
50. 55. 6. In a mining machine, the combination with a mining tool, of means for operating the same, a wedge slidably mounted on said mining tool, and means for operating said wedge by moving the same relatively to said mining tool to break down material from the mine wall adjacent said mining tool.
60. 65. 7. The combination with loading apparatus having a base member movable over the floor of a mine, of a plurality of hooked levers pivotally mounted on said base member, means mounted on said loading apparatus to break down the material from a mine wall for the handling of said loading apparatus, and means for operating said loading apparatus while the base member

of said loading apparatus is being dragged over the floor of the mine due to the hooked connections with a moving mining machine.

8. The combination with loading apparatus comprising a base frame movable over the floor of a mine and an endless conveyer adapted to extend into an under-cut in a mine wall, of means for breaking down the material above said under-cut and onto said conveyer, and a plurality of hooks pivoted 70 to said base frame for connection to a mining machine which produces the under-cut ahead of the operation of said breaking down means and loading apparatus.

9. In an excavating machine, the combination of a base member, a plurality of vertical guides mounted thereon, said guides being provided with racks, a table reciprocal along said guides and provided with pinions engaging said racks, a mining tool 80 mounted on said table, a wedging member movable with said table and mounted in proximity to said mining tool, means individual to the said pinions for rotating the same to raise and lower different portions 85 of the table, means for operating said mining tool, and means independent of the pinion rotating means for operating the wedging member regardless of the position and inclination of the table.

10. In an excavating machine, the combination of a base member, a vertically movable support, a vertical guide for the forward end of said support, a vertical guide for the rear end of said support, said guides and 100 support being provided with means interengaging therebetween for imparting a vertical movement to different portions of said support, a mining tool carried by said support, means for operating said mining tool, 105 a wedging member carried by said support in proximity to said mining tool, and means for operating said wedging member independently of the position and inclination of said support.

11. In an excavating machine, the combination with an axially movable drilling tool, of a wedge mounted on and reciprocable along said tool with the tool.

12. In an excavating machine, the combination with a support, of a tool threaded in said support, means for rotating said tool, and a wedge moved by said tool into the cavity made by said tool, said wedge being adapted to break down the material to be 120 mined.

13. In an excavating machine, the combination with a drill, of a drill rod, a wedge device supported by and reciprocable along said rod, a stop on said rod to operate said wedge, and means for cooperatively driving said drill and wedge device into the material to be mined.

14. In an excavating machine, the combination with a support, of means for raising 130

- and lowering the ends of said support independently to tilt said support, a wedge reciprocably mounted on said support, and a drill, also mounted on said support and 5 operatively related to the wedge, said drill being provided with means for driving the wedge into a hole made by the drill.
15. In an excavating machine, the combination of a support, a drill carried by said support, a wedge reciprocable along said drill, and a stop on said drill to operate upon the wedge.
16. In an excavating machine, the combination of a support provided with a guideway, a drill journaled on said support, a wedge reciprocably mounted in said guideway and in slidable engagement with said drill, and a stop on said drill to operate upon said wedge.
- 20 17. In an excavating machine, the combination of a support provided with a guideway, a drill journaled on said support, and a wedge reciprocably mounted in said guideway and in slidable engagement with said 25 drill, said drill being provided with means for driving the wedge into the hole made by said drill.
18. In an excavating machine, the combination with a drill for excavating a cavity 30 in the material to be mined, a wedge reciprocably mounted on said drill, and a driving device reciprocably mounted on said drill and adapted to impinge said wedge to drive it into the cavity made by said drill.
- 35 19. In an excavating machine, the combination with a drill, of a wedge reciprocably mounted on said drill with the smaller end of the wedge forward, a hammer slidably mounted on the drill and adapted to impinge said wedge, resilient means for driving the hammer forward against said wedge, and means for retracting said hammer against the action of said spring, the last 40 said means being adapted to release the hammer after it has been retracted against the action of said resilient means.
20. In an excavating machine, the combination of a support, cutting means carried by said support, breaking down means following said cutting means and entering the cut produced thereby, and automatic mechanism for imparting repeated blows to said breaking down means while said cutting means continues in operation.
- 55 21. The combination with cutting mechanism, of means for operating said cutting mechanism to produce an incision in a mine wall, a wedge to enter said incision, and automatic means for striking one end of said 60 wedge to effect dislodgment of material from the mine wall adjacent said cutting mechanism.
22. In an excavating machine, the combination of a support, cutting means carried 65 by said support, breaking down means car-
- ried by and following said cutting means by entering the incision produced by the latter, a hammer for imparting a blow to the breaking down means after the cutting means reaches a predetermined depth of cut 70 and while said cutting means is still in operation, and means for operating said hammer.
23. In an excavating machine, the combination of a support, cutting means carried 75 by the support, breaking-down means carried by and following the said cutting means into the material, spring controlled means for imparting a blow to the breaking-down means, and means for retracting the said 80 spring controlled means.
24. In an excavating machine, the combination with cutting mechanism, of a reciprocable wedge device supported by said cutting mechanism, a stop on said cutting mechanism to operate said wedge, and means for co-operatively driving said cutting mechanism and wedging device into the material 85 to be mined.
25. The combination with a mining tool, 90 of means for operating the same, a wedge entering the cut produced thereby and while still in operation, and means for automatically striking said wedge a series of hammer blows in succession to dislodge the material 95 adjacent to said cut.
26. The combination with rotary cutting mechanism, of a wedge for breaking down material adjacent the cut produced by said cutting mechanism, and automatic means 100 for moving said wedge into said cut after the cutter has made a predetermined number of revolutions.
27. The combination with a mining tool, 105 of a shaft connected to said mining tool, a wedge mounted on said shaft, means for guiding said wedge to hold it from turning while permitting movement thereof along said shaft, and means carried by said shaft for pushing the wedge into the opening produced by said mining tool.
28. The combination with a mining tool, 115 of a wedge, means for preventing the rotation of said wedge and restricting it to a straight line movement, and means movable with the forward movement of said mining tool for operating said wedge by striking one end thereof, to move the same longitudinally.
29. The combination with a mining tool, 120 of a shaft connected thereto, a wedge, means for restricting the movement of said wedge to a predetermined path of travel, and a hammer device connected to said shaft to receive power therefrom and movable longitudinally with the shaft into position to act on said wedge.
30. The combination with a plurality of mining tools, of a plurality of shafts connected thereto, a plurality of wedges, one on 125
- 130

- each of said shafts, means for operating said mining tools, and means for simultaneously moving said wedges forward relatively to said tools into positions to break down material adjacent said mining tools. 5
31. The combination with a plurality of rotary cutters, of feed mechanism for said cutters comprising a corresponding number of screw-threaded shafts, one connected to 10 each of said cutters, a plurality of rods connecting said cutters and said screw-threaded shafts, one for each of said cutters, a plurality of wedges, one mounted on each of said rods, a plurality of guideways, one for each of said wedges to limit the movement thereof to straight line movements and prevent their rotation on said rods, a plurality of stops, one on each of said rods, for engaging said wedges to move the same forward as the cutters are fed forward, and a plurality of automatically operated hammer devices, one connected to each of said shafts and movable along said guideways for operation on the wedges when the latter are engaged by said stops. 20
32. The combination with a mining tool, of means for operating the same, a wedge, a hammer, a spring associated with said tool, to enter the incision made thereby, means for placing said spring under compression, and means for freeing the spring to permit it to operate said hammer against said wedge to break down material from a mine wall. 30
33. The combination with a mining tool, of means for operating said mining tool, a breaking down device co-operatively related to said mining tool, and automatic mechanism for striking said breaking down device successive blows to break down material from a mine wall where operated by said mining tool. 40
34. In a mining machine, the combination with a base frame comprising a plurality of vertical gear rods, of a motor mounted on said base frame, a supplemental frame, a mining tool mounted on said supplemental frame, means comprising gearing on said supplemental frame acting on said gear rods for adjusting the height and inclination of said supplemental frame together with the tool mounted thereon, and power transmission gearing between the said motor on the base frame and said mining tool on the adjustable supplemental frame. 50
35. The combination with a main frame, of a motor mounted thereon, a table-like supplemental frame movable to various inclined positions, cutting and breaking down mechanism mounted on said supplemental frame, transmission gearing mounted partly on the main frame and partly on the supplemental frame for operating said cutting and breaking down mechanism, and a sliding power transmitting shaft between the gearing on the main frame and the gearing 60
- on the supplemental frame to permit tilting of said supplemental frame together with the mechanism mounted thereon to various inclined positions up or down. 70
36. The combination with a main frame, of a supplemental frame, of means for lifting and lowering said supplemental frame, a mining tool mounted on said supplemental frame, a motor mounted on said main frame, power transmission gearing connected between said motor and said mining tool, means for adjusting the inclination of said supplemental frame together with the said mining tool thereon either upwardly or downwardly, a conveyer on said main frame, and means for breaking down material from the mine wall near said mining tool onto said conveyer. 80
37. The combination with a main frame, of a table-like supplemental frame, cutting and breaking down mechanism mounted on said supplemental frame, means for lifting and lowering said supplemental frame to various horizontal positions, mechanism for tilting said supplemental frame and the cutting and breaking down mechanism mounted thereon to various inclined positions either up or down, a motor on said main frame, and power transmission gearing between said motor and said cutting and breaking down mechanism comprising a sliding shaft to maintain driving connections for various heights and inclinations of said supplemental frame. 90
38. In a mining machine, the combination with a conveyer adapted to extend into an under cut in a mine wall, of cutting mechanism above said conveyer, and a wedge apparatus slideable with reference to said cutting mechanism for breaking down material from the mine wall onto said conveyer. 100
39. In a mining machine, the combination with a mining tool, of means for operating the same, a wedge slidably carried by said mining tool, and means for operating said wedge by moving the same relatively to said mining tool to break down material from the mine wall adjacent said mining tool. 110
40. The combination with a mining tool, of a shaft connected to said mining tool, a wedge carried by said shaft, means for guiding said wedge to hold it from turning while permitting movement thereof along said shaft, and means carried by said shaft for pushing the wedge into the opening produced by the mining tool. 115
41. In an excavating machine, the combination with an axially movable drilling tool, of a wedge carried by and reciprocable along said tool with said tool. 120
42. In a coal breaking and loading machine, the combination of a frame, a conveyer on the frame adapted to enter a horizontal undercut in the coal, a cutter on the frame above the conveyer, means for ad- 130

vancing the cutter into the coal, and means carried by the cutter and relatively movable with respect thereto for entering the opening formed by the cutter and engaging the coal above the conveyer to break it down.

43. In a coal breaking and loading machine, the combination of a frame, a conveyer on the frame adapted to enter a horizontal undercut in the coal and to lie at an angle to the face of the coal, a continuously acting cutter on the frame above and vertically separated from the conveyer, means for moving the cutter with respect to the conveyer bodily forward along a path at an angle to the coal face and parallel to the conveyer to advance it into the coal, and means for breaking the coal down upon the conveyer.

44. In a coal breaking and loading machine, the combination of a frame, a conveyer on the frame adapted to enter a horizontal undercut in the coal and to lie at an angle to the face of the coal, a cutter on the frame above the conveyer, means for bodily moving the cutter longitudinally with respect to the conveyer to advance it into the coal, and means carried by the cutter and relatively movable with respect thereto for entering the opening formed by the cutter and engaging the coal above the conveyer to break it down.

45. In a coal breaking and loading ma-

chine, the combination of a frame, a conveyer mounted on the frame and adapted to enter a horizontal undercut in the coal, an 25 auger carried by the frame above the undercut, means for advancing the auger into the coal, and means carried by the auger operable when the auger is projected into the coal to break the underlying coal down upon the 40 conveyer.

46. In a coal breaking and loading machine, the combination of a frame, a conveyer mounted on the frame and adapted to enter an undercut in the coal, a cutter supported on the frame above the undercut, 45 means for moving the cutter bodily forward into the coal independently of the conveyer and along right lines transverse of the coal face, means for breaking the coal along 50 lines at angles to the coal face and parallel to the conveyer down upon the conveyer, and power actuated devices adapted to bodily move the machine laterally along the face of the coal from one working position 55 to another.

In testimony whereof I have signed my name to this specification, in the presence of two subscribing witnesses, on this 30th day of July, A. D. 1910.

JOHN H. MORGAN.

Witnesses:

F. V. WIDGER,
ERN. R. JANZ.
